ADAPTER FOR A BOMB

Leonard D. Jackson, Alexandria, Va.

Application April 28, 1945, Serial No. 590,864

1 Claim. (Cl. 102—70)

(Granted under Title 35, U. S. Code (1952), sec. 266)

This invention relates to an adapter for a bomb and is particularly adapted for use on smoke bombs of the marine type adapted to be dropped from an aircraft in flight or launched from the deck of a vessel. Heretofore such marine bombs could only be used for marine operations because of the water pressure controlled firing mechanism employed therewith. It has been found that these bombs could be of service during land operations provided the bombs were adapted to fire upon striking terra firma.

The present invention relates to an adapter adapted to be secured to the nose of a marine smoke bomb thereby to provide means for firing the bomb not only when the bomb strikes the water but also when the bomb strikes the land whereby the bomb can also be used advantageously during land operations.

The principal object of the present invention is to provide a new and improved adapter secured to the nose of a marine smoke bomb of the present type whereby the bomb can be fired either by striking the land or the water.

Another object of the invention is the provision of a new and improved adapter secured to a marine smoke bomb for igniting the pyrotechnic material therein when the bomb comes into contact with land or water, as the case may be, after the bomb is released from an aircraft in flight at a low altitude.

Another object of the invention is the provision of a new and improved adapter secured to a marine smoke bomb for actuating the firing unit within the bomb upon a slight impact of the bomb with either land or water.

Another object of the invention is the provision of a new and improved adapter for a marine smoke bomb having means releasably secured thereto for preventing the premature firing of the bomb until the bomb has been released from an aircraft in flight.

A still further object is to provide a new and improved adapter detachably secured to a marine smoke bomb whereby the bomb is converted into an amphibious weapon.

Still other objects, novel features and advantages of the invention will become apparent from the following description taken in connection with the accompanying drawings, wherein:

Fig. 1 is a fragmentary view of a marine smoke bomb partly in section and partly in elevation and showing the adapter secured thereto;

Fig. 2 is an enlarged plan view of the adapter in a safety or unarmed condition;

Fig. 3 is an elevational view of the device of Fig. 2;

Fig. 4 is a sectional view taken on line 4—4 of Fig. 3;

Fig. 5 is a sectional view taken on line 5—5 of Fig. 2;

Fig. 6 is an enlarged fragmentary sectional view of the marine smoke bomb showing the adapter secured thereto and in armed position, and

Fig. 7 is a view similar to Fig. 6 but showing the adapter in the firing position.

Referring to the drawings in detail for a more complete understanding of the invention, the adapter disclosed

thereon is generally indicated by the reference character 10 and is adapted to be secured to a marine smoke bomb 11 of a well known pressure type whereby the bomb will fire on coming into forcible contact with either land or water. The bomb 11 comprises a casing 12 containing a quantity of smoke producing mixture 13 therein, the usual impact fuse assembly 14 comprising a nipple 15 having an enlarged head 16 and a screw threaded shank 17 adapted to have threaded engagement with a threaded opening 18 provided in the casing 12 at the leading end or nose of the bomb 11. The nipple 15 encloses the usual frangible impact disk 19 composed of paper or the like, impact firing pin 21 including a coil spring 22 for retaining the firing pin in safe position, a primer 23 arranged within the usual retainer 24, and a retaining ring 25 for retaining the impact disk 19, firing pin 21 and the spring 22 within a bore provided in the nipple 15, ring 25 having an opening 26 therein.

A container tube 27 is secured within one end of the nipple 15 and extends a predetermined distance into the smoke mixture 13 and is adapted to support a container 28 having a quantity of starter mixture 29 arranged therein for igniting the smoke mixture. Arranged within the container tube 27 is the usual vent tube 31 enclosing the usual time delay fuse 32 having a length of quickmatch 33 arranged in one end thereof in predetermined spaced relation with respect to the primer 23. The other end of the time delay fuse 32 has a plurality of quickmatches 34 arranged therein and the fuse extends into the starter mixture 29, thereby providing means for firing the starter mixture and the smoke mixture after the time delay fuse has been ignited by the primer 23. The adapter 10 comprises a base member 35 composed of metal or any other material suitable for the purpose, having a cup-like recess defined by a flange arranged at one end of the member and adapted to receive the enlarged head 16 on the nipple 15. A plurality of set screws 37 are employed to secure the base member 35 to the enlarged head 16 of the nipple 15. The set screws 37 have threaded engagement with threaded openings 38 provided in the base member 35 and are adapted to seat in recesses 36 provided in the enlarged head 16 when the screws are driven home, thereby securely holding the adapter to the enlarged head 16 attached to the leading end or nose of the bomb.

A bearing member generally indicated by the reference character 41 comprises an enlarged body portion 42, having a reduced threaded nipple 43 integrally connected thereto, the nipple being in threaded engagement with a threaded opening 44 provided in the base member 35 thereby to support the bearing member in axial relation with respect to the base member. The bearing member is adapted slideably to support a shaft or plunger generally indicated by the reference character 45. The shaft or plunger 45 comprises an enlarged body portion 46 adapted to have sliding movement within a bore 47 provided in the bearing member 41. The shaft is also provided with a reduced impinging pin 48 integrally connected to the body portion 46 and is adapted to have sliding movement within a reduced bore 49 also provided in the bearing member 41. The impinging pin 48 is of such length as to extend into the opening 26 in the retaining ring 25 and within a predetermined distance with respect to the frangible disk 19 for shattering the disk when the plunger 45 moves a sufficient distance within the bearing member 41. A threaded opening 51 is provided in the body portion 46 of the plunger 45 for receiving the threaded portions of a pair of screws 52 adapted to extend radially from opposite sides of the body portion 46. The screws are of such length as to extend into diametrically opposite slots 53 provided in the body portion 42 of the bearing member 41 thereby permitting the plunger to slide a predetermined

distance within the bearing member 41 and also providing stops to prevent the plunger from becoming disengaged from the bearing member.

The end of the body portion 46 opposite the end having the impinging pin 43 thereon is provided with a reduced stud 54 and a washer 55 arranged thereon, the washer 55 having an opening 56 therethrough, through which the stud 54 extends and the stud is of such length as to extend also through an opening 57 provided in a cup-shaped member 58. It will be understood, however, that the washer 55 and cup-shaped member 58 may be secured to the stud 54 in any suitable manner such, for example, as by solder, riveting or the like. It will also be understood that the washer 55 and the cup-shaped member 58 may also be soldered or spot welded together if desired. A U-shaped safety spacer generally indicated by the reference character 59 and comprises a pair of legs 61 connected by a bridge member 62. The safety spacer is adapted to be inserted about the sliding shaft or plunger 45 between the washer 55 and the bearing member 41, the legs 61 thereof having abutting relation with respect to the bearing member 41 and the washer 55 thereby preventing axial movement of the plunger 45 from an initial safe position and the premature firing of the bomb. An opening 63 is provided in each leg 61 of the U-shaped spacer 59 and the usual arming wire 64 is adapted to extend therethrough, thereby preventing displacement of the safety spacer 59 until the bomb is launched. A coil spring 65 is arranged between the body portion 46 of the plunger 45 and the bridge member 62.

In operation, when the bomb is released from an aircraft in flight the arming wire 64 is withdrawn from the openings 63 in the safety spacer 59 as the bomb falls away from the aircraft whereby the spring 65 expands and forces the spacer away from the adapter thereby releasing the plunger and arming the bomb.

When the cup-shaped member 58 comes into contact with either land or water, as the case may be, the plunger 45 is forced through the frangible disk 19 and engages the impact firing pin 21 which is forced against the tension of the spring 22 into the primer 23, firing the primer 23, thereby causing ignition of the quickmatch 33 in the time delay fuse 32 which in turn ignites the time delay fuse. It will be understood, however, that, as is well known in devices of this character, a predetermined period of time such, for example, as several seconds, will elapse after the primer 23 has been fired before the time delay fuse 32 ignites the quickmatches 34 in the other end of the time delay fuse 32 thereby igniting the starter mixture 29, which, in turn, ignites the smoke producing mixture 13 within the casing 12 of the bomb 11 to produce smoke therefrom.

It will be understood, however, that the adapter provides means whereby the present marine smoke bomb is readily converted into an amphibious weapon which can be launched from an aircraft in flight traveling at an extremely low level or from the deck of a ship 12 feet or more from the surface of a body of water for the reason that by the provision of the aforesaid cup-shaped member 58 secured to the plunger 45, the bomb is caused to be fired in response to a slight impact received thereby.

Although the adapter has been described in connection with a marine smoke bomb of the present well-known type, it will be understood that the adapter 10 may be employed, if desired, with various other types of bombs such, for example, as demolition bombs, fire bombs, explosive bombs and the like.

The many advantages of the adapter constructed in accordance with the present invention will be readily apparent to those skilled in the art from a consideration of the foregoing description and drawings, and although a

preferred embodiment of the device is illustrated and described, it is to be understood that changes in the details of construction and in the combination and arrangement of parts may be resorted to which fall within the scope of the invention as claimed.

The invention described herein may be manufactured and used by or for the Government of the United States of America for governmental purposes without the payment of any royalties thereon or therefor.

10 What is claimed as new and desired to be secured by Letters Patent of the United States is:

An adapter for converting into an amphibious weapon a marine bomb including a nipple having an enlarged head disposed exteriorly of the bomb at the nose thereof and a central bore with a firing pin slidable therewithin and adaptable to be forced inwardly in response to impact with water to fire the contents of the bomb, said adapter comprising, in combination, a base member having a cup-like recess defined by a flange arranged at one end of the member and adapted to receive said enlarged head, a bearing member connected to said base member, said bearing member having a longitudinal bore therein, an elongated plunger mounted for sliding movement in said longitudinal bore, said bearing member including an enlarged portion, said enlarged portion having slots therein disposed on opposite sides of said plunger, transversely-extending elements secured to said plunger and disposed in said slots respectively, said elements providing for retaining the plunger engaged with the bearing member and for movement of the plunger over a predetermined distance, screws passing through said flange and adapted to seat in recesses in said enlarged head for securing the base member thereto with the longitudinal bore of the bearing member in axial alignment with the nipple bore and with one end of said plunger adjacent the firing pin, a cup-shaped member secured to the other end of said plunger, and means for normally holding said one end of the plunger spaced from the firing pin, said last-named means comprising a U-shaped member consisting of a pair of parallel legs and an interconnecting end wall, said last-named member being normally disposed about said plunger with said parallel legs interposed between said enlarged portion and said cup-like member, a biased compression spring secured to said end wall and disposed between the end wall and the plunger with the axis of bias of the spring generally parallel to said legs and biasing them to a position free of the plunger and bearing member, said legs having a pair of openings therein near the free ends thereof with an opening in each of the legs respectively, said openings being aligned, and a pull wire passing through said openings and normally disposed at the side of the plunger opposite to the spring for retaining the U-shaped member normally disposed about said plunger, said wire being adapted to be pulled to withdraw the wire from the openings and release the U-shaped member for action of the spring bias; whereby the plunger is freed for movement to force the firing pin inwardly to fire the contents of the bomb upon impact of the cup-shaped member with land or water.
